[57] CLAIM

The ornamental design for a separable holder for keys and the like, substantially as shown.

DESCRIPTION

FIG. 1 is a front perspective view of a separable holder for keys and the like showing my new design;
FIG. 2 is a front elevational view thereof;
FIG. 3 is a side elevational view thereof, from the left side of FIG. 2;
FIG. 4 is a side elevational view thereof, from the right side of FIG. 2;
FIG. 5 is a rear elevational view thereof;
FIG. 6 is a top plan view thereof; and
FIG. 7 is a bottom plan view thereof.
